UNITED STATES PATENT OFFICE.

HERMAN C. MUELLER, OF MILWAUKEE, WISCONSIN.

SOUND-REPRODUCING DEVICE.

Application filed October 30, 1926. Serial No. 145,138.

My invention relates to a cone type of loud speaker more especially intended for use in connection with a radio receiver and has for its object the provision of a device 5 of the character mentioned adapted to reproduce the natural tonal quality of the broadcast signals.

The invention also has as an object a construction wherein the pole pieces and electro- 10 magnet or coil are so mounted relative to the permanent magnet, that the shortest possible magnetic path is provided; that is to say the pole pieces and coil are mounted directly and wholly within the magnetic 15 field of the permanent magnet.

Another object of the invention is to provide a device wherein the pole pieces extend substantially flush with the outer 20 sides of the permanent magnet and there- fore beyond the sides of the coil.

The above enumerated objects and others, as well as advantages inherent in my device, will all be more fully comprehended from the following detailed description of the 25 accompanying drawings, wherein—

Figure 1 is an elevation of my improved cone loud speaker.

Figure 2 is a cross-section taken substantially on the line 2—2 of Figure 1 looking 30 in the direction of the arrows.

Figure 3 is a sectional view taken on the line 3—3 of Figure 2 looking in the direction of the arrows.

Figure 4 is an elevation of the outer cone 35 mounting with portions of the outer cone and its mountings broken away.

Figure 5 is a sectional elevation of the magnets and mountings and showing a portion of the holding member or plate.

Figure 6 is a detail view in perspective 40 of the inner cone.

Figure 7 is a detail perspective view of a pole piece separating and armature support holding member.

Figure 8 is a perspective view of my improved armature.

Figure 9 illustrates a modification of my device, with the outer cone and its mounting partially broken away and shown in 50 section and with a portion of the magnet holding shell being shown.

Figure 10 is a perspective view of a modified form of inner cone.

The invention as disclosed in the drawings 55 comprises a suitable standard or support 15 for holding the unit which is pref-

erably mounted in a suitable housing or shell 16. The shell is provided with a base plate or disc 17 shown preferably provided with an annular shoulder 18 and a central opening 19. The plate or disc 17 adjacent to its outer perimeter is also shown provided with an opening 20.

One side of the plate 17 has a permanent magnet 21 mounted thereon; the magnet 21 with its associated parts being held in place by a cross-bar 22 which straddles one leg or side of the permanent magnet 21 and is shown removably secured to the plate or disc by screws 23. The ends of the cross-bar 22 are provided with suitable binding posts 24, 24, to receive the various lead lines; one of the leads or terminals from the output end of a radio receiver being shown at 25.

The holes in the cross-bar 22 through which the fastening screws 23 pass are preferably provided with insulating washers to prevent contact between the fastening screws 23 and the supporting bar 22; and the binding posts 24 are also provided with suitable washers between the supporting bar and the nuts on the binding posts for proper insulation.

The permanent magnet 21 is provided 85 with pole pieces 26, 27, which are preferably formed and secured wholly within the permanent magnet; that is to say the sides of the pole pieces are bent substantially at right angles to the body or base portion 90 with the ends of the base portion bent outwardly in opposite directions to the sides and forced into clamping relation with the sides of the permanent magnet adjacent to the ends so as to have the pole pieces disposed entirely within the permanent magnet. The pole pieces 26, 27 are disposed 95 toward each other and in slight spaced relation. The pole pieces receive an electromagnet or coil 28 which is preferably of the oblong formation shown in Figures 2 and 5, with the flat sides flush with the inner sides of the pole pieces, so that the core of the coil or passage through the coil will be disposed at a point coincident with 100 the spacing between the opposing pole pieces 26, 27.

The core of the magnet is preferably of some non-magnetic material and in the preferred embodiment of my invention is of 110 the general configuration shown at 29 in Figure 5 so that the space within the core 29

is adapted to receive the holding member 30 shown in Figure 7.

The support holding member 30 consists of a suitable plate, the opposite sides whereof are bent at right angles to the body portion and therefore into parallel relation as shown at 31, 31; and these sides extend slightly beyond the body portion to provide the shoulders 32. These shoulders extend 10 in between the opposing pole pieces 26, 27, with the ends of the pole pieces resting thereon, as clearly shown in Figures 2 and 3. The holding member 30 is provided with a transverse slot 33. The holding member 15 30 fits into the core 29 of the electro-magnet or coil 28 with the ends or shoulders 32 protruding from the core as previously stated and this support holding member and separator provides a suitable mounting for the 20 armature 34 shown in detail in Figure 8. The width of the armature is such that it may fit in between the bent sides 31, 31 of the pole piece separator and support holding member 30.

25 The armature 34 is made of thin sheet material and in order that vibration within the armature itself may be eliminated, the armature is provided with a longitudinally disposed rib or rigidifying surface 35. One 30 end of the armature 34 is shown provided with an extension or lip 36 apertured for connection with the stylus rod or pin 37 which is secured to the armature so as to transmit the vibrations of the armature to a 35 stylus bar 38. The armature 34, at opposite sides, is provided with opposing slits adapted to receive the ends of a bridge or feather 39 made of thin sheet material. The ends of the feather or bridge extend toward one 40 longitudinal side of the bridge and are disposed through the slits in the armature, with the protruding ends bent in opposite directions on the opposite side of the armature. The bridge or feather is adapted to fit into 45 the slot 33 of the pole piece separator member 30 and provide a rocking or tilting point for the armature. As the pole piece separator member 30 comes into contact with one side of the core 29, as clearly shown in 50 Figures 3 and 5, it is apparent that the bridge or feather 39 will be held from too far insertion through the slot 33 and the armature therefore maintained in proper position; dropping of the armature toward 55 the opposite side of the coil-core being prevented by reason of the connection with stylus-rod 37.

The stylus bar 38 which is made of suitable and comparatively thin sheet metal is 60 provided preferably with a longitudinal rib or rigidifying surface 40, see Figure 3, to prevent lateral flexing of the stylus bar. Adjacent one end, the stylus bar is offset or given a somewhat angular formation, as 65 shown at 41 in Figure 3, so as to provide a

V-shaped notch or depression to receive the flared end of the stylus member 42. The end of the stylus bar, adjacent to the off-set or notched portion thereof, is fixedly secured to a bracket 43 mounted on the base or disc 70 17 at a point adjacent to the opening 19, at the center of the plate as clearly shown in Figure 3. The stylus bar 38, at a point adjacent to where it is connected with the rod or pin 37, is shown provided with a short 75 arm 44, see Figure 4, which will prevent lateral movement of the stylus bar at the point of connection with the stylus bar or pin 37. The end of the short arm 44 is suitably connected to the base plate or disc 17, as shown at 45 in Figure 4; it being understood that the short arm or extension 44 is of thin resilient sheet material in order that proper movement of the stylus bar 38, induced by the armature 34 through stylus pin or rod 80 37, may take place.

85 The stylus 42 is shown preferably in the nature of a threaded pin, see Figure 3, with the inner end flared or formed of thin sheet metal which rests edgewise in the notch in the stylus bar 38; the inner end of the stylus being formed as described to permit lateral flexing or vibration of the stylus, namely in a direction longitudinally of the stylus bar 38. The stylus 42 is connected to the apex 90 of an inner cone 46 which is preferably of sheet metal and which in turn is mounted on or provided with resilient posts or supports 47. In the construction illustrated in Figures 2, 3 and 4, the posts 47 consist of angularly bent thin sheet metal with the upturned ends or legs secured in any suitable manner to the flanged perimeter 48 of the cone 46; the supports or posts being 95 equally spaced apart and adapted to permit vibration of the cone induced through the action of the stylus 42. The stylus 42 is clamped to the cone 46 by suitable means, as for example the nuts 49 screwed on the stylus above and below the cone 46, as shown 100 in Figure 3. The spring posts 47 are suitably secured on the annular shoulder 18 of the base plate 17 as shown in Figure 4 and are therefore disposed inwardly over the dished face of the base plate or disc 17.

105 Arranged in spaced relation with the inner cone 46 and mounted on the stylus 42 is an amplifier cone 50 which may be of suitable paper or fiber and of suitable dimensions. The amplifier cone 50 is secured in place by 110 being clamped between a pair of cone discs 51. The cone discs are of thin sheet material and of suitable dimensions and are slightly dished so that the perimeters will grip the amplifier cone 50 circumferentially 115 at a point removed from the center of the cone 50 instead of at the apex of the amplifying cone 50 and therefore nearer to the point where the vibrations are set up in the amplifying cone 50. The inner cone disc 120 125

51 rests on the nut 49, while the outer cone disc is held in place on the end of the stylus 42 by means of a nut 52.

The stylus 42, as is apparent from the 5 construction shown in Figure 3, transmits vibration to all of the cones and by mounting the amplifier cone in the manner shown and described, possibility of distortion of the inner cone 46, when fastening the amplifier cone on the stylus is prevented—as 10 would be the case if the amplifier cone 50 was clamped immediately on and in contact with cone 46 and held in place by the outer disc cone 51. If the amplifier cone 15 50 was placed on the cone 46 and clamped in place by the outer cone disc 51 and nut 52, there would be great possibility of distortion of the inner cone 46, with the result that the unit would be thrown out of 20 adjustment, its functioning hampered and the proper tone qualities of the unit materially affected. With the construction as shown in the drawings, pressure on the inner cone 46 by the amplifier cone and its clamping disc 25 cones is avoided.

In Figure 10 I illustrate a modification of the inner cone 46; the modification involving a single piece member comprising the cone portion 53 formed integral with the 30 spring supports or legs 54 which are bent into the angular formation shown and with the free ends bent outwardly as shown at 55. These apertured ends 55 are adapted to be secured on the shoulder adjacent the outer 35 perimeter of the supporting plate or disc 17 in the manner previously stated.

I have shown what I believe to be the best embodiments of my invention; the same having been described in terms employed merely 40 as terms of description and not as terms of limitations as structural modifications are possible and may be made without, however, departing from the spirit of my invention.

What I claim is:—

45 1. A device of the character described, comprising a supporting plate, a permanent magnet placed on one side of the plate, pole pieces secured to the ends of the magnet in opposing relation and within the magnet, 50 a coil mounted within the pole pieces with the core of the coil aligned with the spacing between the pole pieces, an armature tiltably mounted in the core and provided with an extension extending beyond one of the 55 sides of the pole pieces, a stylus bar secured at one end on said supporting plate and provided with a notch, a rod intermediate of the extension of the armature and one end of said stylus bar and connected thereto, a 60 stylus mounted in the notch of the stylus bar, an amplifying cone mounted on the stylus and means whereby the amplifying cone is secured on the stylus and clamped at a point removed from the apex thereof.

65 2. In a device of the character described,

a supporting member, a bracket secured on one side of the member, a stylus bar, one end whereof is secured to said bracket, said bar being provided with a rigidifying surface disposed longitudinally thereof and depressed adjacent one end; a stylus having a thin sheet portion mounted in said depression, a metallic cone provided with spring supports whereby the cone is held in yielding spaced relation with the supporting member, said cone being also secured at its apex to the stylus, and an amplifying cone secured to the stylus in spaced relation with said first mentioned cone.

3. In a device of the character described, 80 a supporting member, a stylus bar mounted at one end on said member, said stylus bar being of thin sheet material and provided with a rigidifying surface disposed lengthwise thereof, a stylus having a thin flattened end disposed transversely of the stylus bar and mounted thereon whereby rocking of the stylus is prevented and flexing of the stylus in a direction lengthwise of the stylus bar permitted, and sound radiating means 85 secured to the outer end of the stylus.

4. In a device of the character described, 90 a supporting member, a stylus bar of thin sheet material with one end thereof secured in place on said supporting member, the stylus bar adjacent to the point of mounting being formed to provide a socket, a stylus provided with a thin sheet inner end mounted in the socket of the stylus bar, said inner end being arranged to permit flexing of the 95 stylus in a direction lengthwise of the stylus bar, a cone, the perimeter whereof is provided with spring supports whose outer ends are secured to the supporting member and the cone held in spaced relation with said member, the apex of the cone being apertured for passage of the stylus therethrough and being clamped to the stylus, a radiating cone apertured at its apex for passage of the 100 stylus, and clamping means disposed on the inner and outer sides of said cone and adapted to grip the latter circumferentially at a point removed from the apex.

5. In a device of the character described, 110 a supporting plate, a thin sheet stylus bar mounted edgewise on the supporting plate and provided with a rigidifying surface lengthwise thereof, a stylus provided with a thin flexing end secured on the stylus bar, and radiating means secured to the stylus.

6. In a device of the character described, 120 a supporting plate, a bracket on said plate, a stylus bar secured at one end to said bracket, a stylus provided with a flexing end secured on the stylus-bar, and radiating means secured to the stylus.

7. In a device of the character described, 130 a supporting member, an inner cone yielding mounted on and in spaced relation with the member, a stylus disposed through

the apex of the cone and secured thereto, an outer cone arranged in spaced relation with the inner cone and mounted adjacent to its apex to the stylus, and means secured 5 to the stylus whereby the outer cone is clamped in place and distortion of the inner cone prevented.

8. In a device of the character described, a supporting member, a stylus-bar mounted 10 on said member, a stylus mounted at one end on said stylus-bar, a cone disposed above the stylus-bar and secured at its apex to said stylus, and resilient supports intermediate 15 of the periphery of said cone and the supporting member.

9. In a device of the character described, a supporting plate, a stylus-bar secured at one end on said plate, means whereby lateral flexing of the stylus-bar is prevented, 20 a stylus provided with a thin flared end mounted edgewise on the stylus-bar with said end arranged transversely of the stylus-bar, a radiating cone, and means whereby said cone is gripped at a point removed from 25 its apex and secured to the stylus.

10. A sound reproducing device comprising a supporting plate provided with an opening, a permanent magnet secured to said plate, pole-pieces secured to the ends of 30 said magnet and arranged wholly within the magnet, a coil arranged within the opposing pole-pieces, an armature arranged within the coil and provided with an extension disposed beyond the sides of the coil 35 and the pole-pieces, a bridge arranged transversely of the armature and within the coil, a stylus-bar mounted at one end on said plate while the opposite end is provided with a laterally disposed arm secured to said plate, 40 a stylus-rod secured at one end to the armature extension and disposed through the opening in said plate with the other end secured to the stylus-bar, a stylus provided with a thin flared end arranged transversely

of and secured to the stylus-bar, and amplifying means secured to said stylus. 45

11. A sound reproducing device comprising a supporting member, a permanent magnet arranged on one side of said supporting member, a clamping bar whereby the magnet 50 is secured to said member, said bar being provided with terminal posts, pole-pieces arranged within the magnet and secured thereto, a coil within the pole-pieces, a pole-piece separator arranged within the coil, an armature within the coil and having a portion disposed beyond the outer sides of the coil 55 and the pole-pieces, a bridge intermediate of one side of the armature and said pole-piece separator, a stylus-bar arranged edge-wise on the opposite side of said supporting member with one end provided with a laterally disposed resilient arm, a stylus-rod intermediate of said armature portion and the end of the stylus-bar provided with said arm, a stylus having a thin flared end mounted edgewise on and transversely of the stylus-bar, an inner cone secured at its apex 60 to said stylus and provided at its perimeter with resilient supporting portions secured to said supporting member, an outer cone arranged in spaced relation with the inner cone, and means whereby said outer cone is clamped at a distance from its apex and secured to said stylus. 65

12. In a device of the character described, a supporting plate, a stylus-bar secured at one end on said plate, a stylus mounted at one end on said stylus-bar, an inner cone resiliently supported on said plate above the 70 stylus-bar and operatively connected at its apex to the stylus which extends therethrough, an outer cone arranged in spaced relation with the inner cone, and means whereby said outer cone is gripped at a distance removed from its apex and secured to the stylus. 75

HERMAN C. MUELLER.
